United States Patent Office

Des. 207,346
Patented Apr. 4, 1967

207,346

TOOL HOLDER

Gilbert F. Lutz, Chesterland, Ohio, assignor to The Warner & Swasey Company, Cleveland, Ohio, a corporation of Ohio

Filed Jan. 17, 1966, Ser. No. 630

Term of patent 14 years

(Cl. D54—13)

FIG. 1

FIG. 2

FIG. 3

FIG. 4

FIG. 5

FIG. 6

FIG. 1 is a top plan view of a tool holder, embodying my new design;

FIG. 2 is a side elevational view thereof;

FIG. 3 is an end elevational view thereof taken from the left of FIG. 2;

FIG. 4 is a bottom plan view thereof;

FIG. 5 is an elevational view of the opposite side thereof; and

FIG. 6 is an end elevational view thereof taken from the right of FIG. 2.

The dot-dash lines shown in FIGS. 2 and 5 are for illustrative purposes only.

What I claim is:

The ornamental design for a tool holder, substantially as shown and described.
